UNITED STATES PATENT OFFICE.

ALBERT SCHUSTER, OF BERLIN, GERMANY.

MACHINE FOR FILLING AND CLOSING MATCH-BOXES.

SPECIFICATION forming part of Letters Patent No. 657,573, dated September 11, 1900.

Application filed October 27, 1898. Serial No. 610,215. (No model.)

To all whom it may concern:

Be it known that I, ALBERT SCHUSTER, a citizen of the German Empire, residing at Berlin, Germany, have invented an Improvement 5 in Machines for Filling and Closing Match-Boxes, of which the following is a specification.

The present invention concerns an improvement in machines for filling match-boxes. 10 The principal effect of the improvement lies in that the friction between the matches, which was formerly inevitable during the whole filling process, has been reduced to a minimum, and that consequently the heads 15 are protected from injury, and that the explosions so frequently occurring are obviated. To this end the separated matches are transported from the charging place to the inner box in the manner that they remain at rest 20 on the conveying medium without change of position or subjection to friction anywhere.

To carry out this invention, a slide or carriage with a compartment having a movable bottom has been chosen. The separated 25 matches, which rest on the movable bottom of this compartment, are received into the compartment so formed by lowering the bottom. The slide or carriage carries the matches received in the compartment until they are 30 under the inner box, which has its opening turned downward. When the slide moves, the matches remain completely at rest and are not subjected to friction between themselves or otherwise. When the compartment 35 of the slide has arrived under the inner box, the matches are, by raising the bottom of the compartment, lifted into the inner box without friction.

The accompanying drawings demonstrate 40 the improvement by fifteen figures.

Figure 1 shows the principal parts of the filling mechanism in side elevation, parts of the machine being in section. Fig. 2 shows the slide or carriage on the table in plan view, 45 some parts being omitted. Fig. 3 represents some parts omitted in Fig. 2 in top view. Fig. 4 shows the piston-shaped bottom of the compartment in vertical section. Fig. 5 is a side view illustrating the position of the inner and 50 the outer boxes before they are pushed one into the other. Figs. 6, 7, and 8 illustrate various working positions of the piston and

the carriage in longitudinal section. Figs. 6^a and 7^a are detail views. Figs. 9 and 10 represent in top view the action of a facing-plate 55 on the carriage, by which the compartment is changed longitudinally during the filling process. Fig. 11 is a sectional view showing the box-holder serving to hold the inner box in exact position. Figs. 12 and 13 are detail 60 views illustrating the action of placing the inner box within the outer one.

The invention relates particularly to the sliding carriage *a*, which reciprocates on a table, the movement of the carriage being 65 limited by the stops *a'* *a''*. (See Fig. 2.) The carriage *a* is rigidly connected with a rectangularly-arranged arm *b*. Over the carriage the reservoir *c* is fixed on the table, Fig. 1, and the matches are laid in the same, heads 70 forward, after coming from the delivery-boxes taken out of other machines. In the reservoir there is a shaking device consisting of a board or bottom piece *c'*, oscillating around the pivot *c''*, and a reciprocating slide 75 *d*. The shaking device serves the purpose of forwarding the matches evenly into a gathering-reservoir *d'*, which forms a continuation of the reservoir *c*, touches with its lower edges the surfaces of 80 the sliding carriage *a* and has a slit at its right side (see Figs. 6 to 8) through which a separating-knife *e*, carried by a block *e'*, moves for the purpose of separating a quantity of matches, corresponding to the depth 85 or capacity of the box to be employed, from the match-pile in the gathering-reservoir *d'*. A piston or forcer *f* is movably arranged between the walls of the reservoir for the purpose of compressing the matches piled in the 90 gathering-reservoir, and this piston is pressed by means of a spring to press on the matches before they are separated. These parts, excepting the sliding carriage *a*, form no part of the invention. They are only mentioned 95 for the better understanding of the invention.

The most essential part of the invention is the sliding carriage *a*. It has an opening or cut-out *g*, Figs. 7 and 9, which corresponds 100 in breadth to the inner width of an inside box, so that an inside box guided over the opening *g* with the edges of its side walls on the longitudinal edges of the opening cannot

fall into the latter. At proper moments the piston g' , the movement of which is limited by a slit and a set-screw g^4 , provided in the guide g^5 , (see Figs. 4, 6, and 11,) is moved to 5 and from the opening.

Transversely and in front of the opening or cut-out g an enlargement of the opening is provided at h , in which a slide h' can move to and fro in the direction of the opening g .

10 (See Figs. 9 and 10.) The slide h' , made in the shape of a plate, forms a movable face wall of the compartment formed by the opening g when the piston g' is lowered. The movement of the slide h' takes place during 15 the reciprocating motion of the sliding carriage a by means of a stationary plate i' , arranged on the table, Fig. 9. This plate can be adjusted, and it has an inclined surface, and on the plate a pulley i , carried by the 20 slide h' , runs back and forth. The roller is journaled in a fork h^2 of the slide. The fork has two lateral lugs k , against which rest two plate-springs i^2 , which tend to press forward the pulley-fork, and consequently the 25 face-wall h' . In the movement of the sliding carriage from right to left in the direction of the arrow 2, Fig. 2, the face-wall is moved by the inclined plane and roller toward the notch g , and so shortens the compartment, while in 30 the movement of the sliding carriage from left to right in the direction of the arrow 1 the face-wall is again pressed back by the plate-springs i^2 , and the compartment is thus lengthened.

35 The movability of the one face-wall of the compartment g has been provided for the purpose of making the matches fall easily out of the gathering-reservoir d' , so that at the moment when the compartment g has been formed 40 under the gathering-reservoir d' , by the descent of the piston g' , to leave the space in the compartment free, the face-wall h' assumes its retracted position, at which time the compartment reaches its greatest length. On the 45 other hand the face-wall serves the purpose of shortening the compartment g to the exact length of the matches at the moment when the compartment g has arrived under the inner box and the matches are to be raised from 50 below into said inner box by the lifting of the piston g' .

The adjustability of the plate i' serves the purpose of regulating the face-wall in its movement in such a manner that matches of 55 varying length and from different factories can be handled in one and the same machine.

A box-holder (see Figs. 1 and 11) serves to retain the inner box precisely at the place provided for filling in the matches. This box-holder consists of a block y , provided with two lateral springs y^2 , which are turned down and slightly bent outwardly at their lower ends, and the block is guided in the frame or horse y^3 . On the frame is attached a spring 65 y' , under which the inner bar is pushed until it rests against the wall of the frame. When the block y is lowered, the springs y^2 catch at

both sides over the inner box, and so regulate its position lengthwise. Laterally the box is held on the one side by the frame y^3 and on the other by a movable hand n , provided with two fingers n' . The hand n is carried pivotally by a part m . This part m is fixed to the table. The spring y' , which holds the inner box from above, furthermore serves the purpose of preventing crushing of the box and damage to the match-heads when the piston g' rises.

The hand n , serving for the holding of the inner box, is held stationary on the table by a jack screwed to the same. The fingers n' , Fig. 3, of the hand are so calculated that their outer edges rest exactly on one wall of the inner box. The inner box lies in front of a shoulder l , attached to the surface of the sliding carriage. This shoulder l moves the box 80 from under the hand n in the direction of the arrow 1 as far as the frame y^3 , when the carriage moves. The box itself passes during its travel under the fingers n' , which are turned slantingly downward, and the box, through 85 the fingers, lifts the hand, so that the box 90 glides from under the fingers n' . As soon as the carriage has finished its movement in this direction and the box touches the frame y^3 the hand falls down and the fingers n' lie in front 95 of the box, holding it in this position during the whole travel of the carriage in the direction of the arrow 2.

An arm l' , (see Fig. 2,) rigidly connected with the carriage a , serves to forward the 100 outer box to the place where the inner box is to be pushed into the outer one, and at that place a bolt o , Fig. 2, sliding adjustably on the table holds the outer box during the return travel of the carriage by means of thin plate-springs p , which extend into the outer box. These plate-springs p also render possible the insertion of the inner box into the outer one, and this operation is executed by means of a slider z . (See Figs. 3 and 5.) Fig. 12 illustrates the bolt o in its rearmost position, with the springs p entering the outer box, so as to form a guide for the inner box, which is pushed into it by the slide z . In this position the bolt o is held by a latch o' ; but when the 115 slide z moves to place the inner box within the outer one this latch is released by the cam projection o^2 , which moves with the slide, and then the bolt o resumes its forward position, (see Fig. 13,) so that the springs p are 120 withdrawn from the outer box at the same time the inner box is thrust into place. The bolt o is operated by a lever m^4 , which is in turn operated by a lever m^3 , and this is operated from a roller m^2 through any suitable 125 connections. The roller m^2 is moved laterally by coming in contact with the end m' of the fixed part m , the roller being supported to move with the carriage. The bolt o may be returned to its forward position by the 130 spring o^4 .

The improvements work in the following manner: In the position represented in Fig. 1 an outer box is in place exactly in front of

the arm l' , Fig. 2, and an inner box before the shoulder l . The separating or dividing knife e has come out of the gathering-reservoir d' , so that the matches in the filling-reservoir c can fall into the gathering-reservoir d' as far as the surface of the sliding carriage a . When the carriage moves in the arrow direction 1, the inner box is guided under the box-holder y and the outer box in front of the bracket o . In this movement of the carriage the two plate-springs y^2 of the box-holder are held up by a lever y^4 catching into the upper slit y^7 of the block y , Figs. 1 and 11, and the position of the lever y^4 is determined by a pawl y^6 , Fig. 1, which catches with its nose under the lever y^4 . During the travel of the carriage a cam l^2 , Fig. 1, fixed on the carriage, slides with its flat side along a lever 2, situated slantingly on its path, and thereby presses the latch y^6 out of its position, so that the lever y^4 presses downward by means of a spring y^5 when the inner box has arrived under the box-holder. In this operation the side springs y^2 are pushed downward with the block, and at the same time the springs y^2 catch over the face sides of the inner box. After the termination of the movement of the carriage in the arrow direction 1 the box is held on all sides and from above after the fingers n' of the hand have set in front of the box. At the limit of the movement of the carriage in the arrow direction 1 the compartment formed by the opening or cut-out g and the piston g' opens in the following manner: On the guide g^5 of the piston g' is pivotally supported a latch g^3 , (see Figs. 4 and 11,) influenced by the pressure of a spring. The latch catches under a shoulder g^2 of the piston g' and holds the piston in raised position until it has arrived under the gathering-reservoir d' . At this time the latch g^3 has come into contact with a stop-cam g^6 , Fig. 1, fixed under the table. This cam disengages the latch g^3 by means of its slanting surface precisely at the moment when the carriage has reached the limit of its motion. The piston g' then falls down by its own weight, leaving the compartment g free for the reception of the matches, which have been divided off by the knife e . (See Figs. 6 and 7.) When the matches fall into the compartment, it has been lengthened by the recession of the movable face-wall h' . (See Figs. 9 and 10.) In the movement of the carriage in the direction 2 the carriage brings the quantity of matches contained in the compartment as far as the inner box, already held by the box-holder. (See Fig. 8.) In this operation the roller i , connected with the movable face-wall h' of the compartment, has passed the slanting plane of the plate i' , whereby the compartment has been shortened by the exact length of the matches. (See Fig. 10.) When the compartment has arrived under the inner box, the piston g' is moved upward again by pressing upon a piston w , which may be oper-

ated by hand and which slides in the table by means of a lever v , pivoting around v' , and when the piston rises the latch g^3 catches again under the shoulder g^2 of the piston g' and holds the piston until the opposite movement of the carriage is accomplished. At the same time the matches have been lifted into the inner box, the opening of which lies face downward, while the piston travels up, and, moreover, an arm w' , fixed on the piston w , has come into contact with a shoulder w^2 of the lever y^4 , Fig. 1, whereby the latter raises the block y of the box-holder, and consequently also the two springs y^2 , while the shoulder of the latch y^6 catches again under the lever y^4 . The inner box can now be slid into the outer box, standing on a slide over the bracket o , by means of the slider z , Figs. 3 and 5, passing between the plate-springs p of the bracket o . At the insertion of the inner box into the outer box a slide-arm Z^2 , rigidly connected with the slider z , in front of which side arm are deposited a row of inner boxes, pushes one or the same in front of the shoulder l on the carriage. At the next travel of the carriage in the direction of the arrow 1 the inner box in front of the shoulder l is again pushed under the box-holder, and an outer box placed in front of the arm l' is pushed into the path c^3 over the bracket o , in which operation the outer box pushes the ready combined match-box—i. e., the inner box inserted in the outer one—toward the end in the path c^3 by as much as its own width, singly, when a considerable quantity is filled and are there caught in baskets or transferred into packing-machines.

The machine can be driven by any known suitable means, and as they are not essential to the invention they are omitted in the drawings.

I claim—

1. In combination in a machine for filling match-boxes, a reciprocating carriage a having a compartment or opening extending therethrough from top to bottom, a holder y above the carriage adapted to hold the box in inverted position over the carriage, a reciprocating piston g' below the reciprocating carriage and arranged to be moved up into the compartment thereof, means for supporting the piston from the reciprocating carriage, a pawl g^3 for holding the piston up, a reservoir d' above the carriage and located to one side of the box-holder y , means for separating a quantity of matches in said reservoir from the main body of the matches, means for releasing the piston g' to allow the same to fall when the compartment arrives under the reservoir d' , a movable face-wall h' for the compartment, means for retracting said face-wall while the matches are dropping from the reservoir into the compartment, means for operating the face-wall inwardly to reduce the size of the compart-

ment and for raising the piston g' and means for uniting the box with its covering portion, substantially as described.

2. In combination, the reciprocating carriage having an opening therein extending vertically therethrough, a movable face-wall h' , a reservoir for the matches above the carriage, springs i^2 for retracting the face-wall to enlarge the opening or compartment and an incline i' for moving the face-wall inwardly in the movement of the carriage, substantially as described.

3. In combination, the reciprocating carriage having a compartment or opening therethrough, a holder y above the carriage, a spring y' under which the box is forced, the two springs y^2 bent outwardly at their lower ends, a movable part guided to move vertically and carrying said springs for determining the position of the inner box during the introduction of the matches, a piston reciprocating vertically through the compartment to introduce the matches to the inner box and means for operating the piston, the said springs y' and y^2 holding the box yieldingly and allowing for different-sized boxes, substantially as described.

4. In combination, a reciprocating carriage having an opening extending vertically there-

of, a plunger working in said opening, means for supporting the plunger on the carriage whereby it moves therewith and forms the bottom of the cavity in the carriage, means above the carriage to feed the matches into the opening, means for holding the boxes in inverted position above the said carriage and means for reciprocating the carriage whereby the opening is moved from the feeding means to the box-holding means, and means for controlling the movement of the plunger, to raise the same flush with the table when the matches are fed into position above the opening, and to lower with the supply of matches supported thereby, substantially as described.

5. In combination, the carriage having an opening to receive the matches, said opening having a movable side wall, means for moving the side wall to increase or diminish the size of the opening, means for delivering the matches to said opening and a piston working in said opening from below, substantially as described.

In testimony whereof I hereunto set my hand in presence of two witnesses.

ALBERT SCHUSTER.
